UNITED STATES PATENT OFFICE.

ALFRED V. DE GRAND, OF ALTON, ILLINOIS.

ROOF ARCH OR WALL FOR COMBUSTION CHAMBERS.

Application filed August 16, 1926. Serial No. 129,466.

This invention relates to combustion chambers, and particularly to the roofs, arches or walls of such structures that are apt to disintegrate or break down, due to 5 the high temperatures to which they are subjected when in service.

The main object of my invention is to provide a roof, arch or wall that is equipped with a novel means for enabling the elements which constitute the active face of same, i. e. the face that is exposed to radiant heat or to the direct action of the flame, to be adjusted so as to eliminate projections on said active face against which the flame 15 will strike and eat into the joints between the elements that compose said face.

Other objects and desirable features of my invention will be hereinafter pointed out.

My invention is applicable to stoker arches 20 and ignition arches, such as are used in boilers and various other kinds of apparatus operated by fuel, and it is also applicable to the roofs and walls of annealing ovens, tube stills or cracking stills, such as are used 25 in the oil industry, and in fact, to any kind of a combustion chamber in which a high temperature is maintained.

Figure 1 of the drawings is a longitudinal sectional view of a roof, arch or wall constructed in accordance with my invention; and

Figure 2 is a transverse sectional view, taken on the line 2—2 of Figure 1.

In my improved roof, arch or wall the elements that constitute the active face of the structure are not permanently mounted upon or immovably connected to a supporting structure, as is now the usual custom, but instead, said elements are mounted on a supporting structure in such a manner that they can be adjusted independently of each other, either to cause the active faces of said elements to align or extend flush with each other, or to permit any one of said elements 40 to be removed or replaced without disturbing the adjacent elements. When my invention is embodied in a stoker, arch or ignition arch, or in a roof for a combustion chamber, the elements that make up the arch 45 or roof will be formed either of solid blocks of refractory material, or blocks provided with renewable face portions, and will be suspended from an overhead supporting structure by a means that can be adjusted 50 so as to raise or lower said blocks independently of each other and thus cause the bot-

tom faces of said blocks to extend flush, thereby forming an arch or roof which is free from projections against which the flame can strike, and thus cause the blocks 60 to spawl and burn. It is, of course, immaterial whether said blocks are arranged so as to form a horizontal arch or roof, or an inclined arch or roof. When my invention is embodied in a vertical wall or upright wall, 65 the supporting structure will be arranged at one side of the elements that constitute the wall, and said elements will be sustained or supported by devices that are capable of being adjusted or moved in a horizontal or 70 substantially horizontal direction.

In the preferred form of my invention herein illustrated the roof, arch or wall is made up of a plurality of tile or other elements, each of which comprises a back portion A and a renewable face portion A', either one or both of which are formed of refractory material, and the face portion A' is detachably connected to the back portion A by a co-operating tongue and groove, 75 as shown clearly in Figure 1. Such a construction is desirable, in that it permits the portion of the roof or arch that is exposed to the direct action of the flame to be renewed quickly and at a low cost, but, as 80 previously stated, the arch or roof can be made up of solid blocks or tile without departing from the spirit of my invention. Any suitable type or kind of supporting structure can be used to carry the elements 85 A and various means can be used to adjust said elements independently of each other and relatively to the supporting structure. In the form of my invention herein illustrated the supporting structure consists of 90 a number of transversely-disposed members B arranged in spaced relation, and a number of longitudinally-disposed members C arranged at substantially right angles to the members B and connected at their ends 95 to same, the members B and C usually being formed from channels or other commercially rolled shapes.

The blocks or elements A are arranged in abutting relation beneath said supporting 105 structure, and each of said blocks is suspended from said supporting structure by a vertically-adjustable rod 1 that passes upwardly through a hole in one member of the supporting structure, and which is provided at 110 its upper end with an externally screw-threaded portion on which a nut 2 is mount-

ed, said nut being arranged above or at the upper side of the supporting member through which the rod projects upwardly, so as to firmly support the rod and also enable it to be adjusted easily to properly position the block or element sustained by the rod. In order to provide for a slight rocking movement of the elements A relatively to the rods 1 that sustain same, so as to facilitate the adjustment of said elements and cause said elements to balance perfectly at any angle of incline, each of the elements A is pivotally mounted on the rod 1 that carries the same. In the form of my invention herein illustrated this desirable result is attained by providing each of the elements A with an upwardly-projecting arc-shaped yoke or substantially inverted U-shaped hanger 3 that is pivotally connected intermediate its ends by a pivot pin 4 to a clevis 5 on the lower end of the rod 1. As shown in Figure 1, the yoke 3 is arranged in a depression or recess in the top face of the element A and said yoke is secured to said element usually by means of transversely-disposed pins 3^a that pass through said element and through the end portions of the yoke. I also prefer to provide each of the hangers 3 with a set of pivot pin holes 4^a arranged in an arc, as shown in Figure 1, so as to permit the hangers 3 to be adjusted relatively to the clevises 5 which carry same.

While I prefer to sustain the elements A by a means of the character above described, due to the fact that the metallic parts of the structure are completely protected from excessive temperatures, and the refractory elements of the structure are capable of being adjusted quickly and easily, I wish it

to be understood that various other means can be used for sustaining and adjusting the tile or elements A of the structure without departing from the spirit of my invention.

Having thus described my invention, 45 what I claim as new and desire to secure by Letters Patent is:

1. In a structure of the kind referred to, a plurality of elements disposed so as to form a roof, arch or wall, a supporting structure arranged above said elements, a vertically-adjustable sustaining device on said supporting structure for each of said elements, clevises mounted on the lower ends of said sustaining devices, arc-shaped hangers 55 attached to said elements and projecting upwardly from same, and a pivot pin for connecting each of said hangers to its co-operating clevis, each of said hangers having a plurality of pivot pin holes arranged in 60 an arc so as to permit the element to which the hanger is secured to be adjusted in an arc relatively to its sustaining device.

2. In a structure of the kind referred to, a plurality of rectangularly-shaped blocks arranged in abutting relationship so as to form a roof, arch or wall, each of said blocks comprising a back portion and a face portion detachably connected to said back portion, an overhead supporting structure, vertically-adjustable rods mounted in said supporting structure, substantially arc-shaped yokes secured to the back portions of said blocks and projecting upwardly from the same, and clevises on said rods pivotally 70 connected to said yokes.

ALFRED V. DE GRAND.
